UNITED STATES PATENT OFFICE.

CHARLES E. CHASE AND OLIN E. HUTCHINGS, OF BELGRADE, MONTANA.

STONE-GATHERER.

1,304,156.

Specification of Letters Patent.

Patented May 20, 1919.

Application filed August 3, 1917, Serial No. 184,325. Renewed October 8, 1918. Serial No. 257,409.

To all whom it may concern:

Be it known that we, CHARLES E. CHASE and OLIN E. HUTCHINGS, citizens of the United States, residing at Belgrade, in the county of Gallatin, State of Montana, have invented certain new and useful Improvements in Stone-Gatherers; and we do hereby declare the following to be a full, clear, and exact description of the invention, such as will enable others skilled in the art to which it appertains to make and use the same.

This invention relates to new and useful improvements in stone pickers or gatherers.

One object of the present invention is to provide a simple and cheap device of this character by means of which the stones can be quickly and effectively gathered.

Another object is to provide a device of this character by means of which the stones are scraped up from the ground, elevated, and deposited in a wagon which is moving at the side of the device.

Other objects and advantages will be apparent from the following description when taken in connection with the accompanying drawing.

In the drawing:

Figure 1 is a side elevation of a stone gatherer made in accordance with our invention.

Fig. 2 is a top plan view of the device.

Fig. 3 is a rear elevation of the device.

Fig. 4 is a perspective view of a portion of the lifting wheel showing the arrangement of the pockets.

Fig. 5 is an enlarged perspective view of a portion of the rake member 24.

Fig. 6 is a vertical longitudinal sectional view taken on the line 6—6 of Fig. 2.

Fig. 7 is an enlarged horizontal sectional view taken on the line 7—7 of Fig. 1.

Fig. 8 is a perspective view of the rear end of the rake member 24 showing the scraping blade 36.

Referring particularly to the accompanying drawing there is shown a horizontal frame which includes the side members 10 and the transverse end members 11. A tongue or draft pole 12 extends longitudinally through the center of the frame and is secured thereto, the said pole also extending a suitable distance forwardly of the frame where it is supported on the fifth-wheel truck 13 having the ground engaging wheels 14. To this truck the draft animals are to be at-

tached, as will be readily understood. Extending transversely of the rear portion of the frame is a shaft 16, and pivotally mounted on this shaft is a rearwardly and upwardly inclined frame 17, the rear end of which carries the shaft or axle 18. On one end of this axle there is mounted the large ground engaging wheel 19. This wheel includes a rim 20, hub 21, and spokes 22. Secured to each of the spokes of the wheel, and to the adjacent portion of the rim, is a pocket member 23.

Secured to the lower side of the main or first-mentioned frame and disposed obliquely and longitudinally from the forward outer corner of the frame to a point below and rearwardly of the axle of the wheel 19, is a bar 24, said bar being provided with downwardly extending rake teeth 25 for scraping action on the ground to drag the stones therefrom. These teeth are held on the bar by the plate 24' and the bolts 25' which latter are disposed through the plate and bar. On the rear end of this bar there is disposed a mold-board-shaped member 36 which is adapted to guide the stones into the pockets of the wheel 19 as the pockets successively reach their lowermost points in the rotation of the wheel. Secured to the lower side of the frame 10 and extending from the other forward corner of the main frame to a point adjacent the intersection of the tongue 12 and the shaft 16, is a second shorter beam 27, also provided with downwardly extending raking teeth 28 which are arranged to draw the stones from that side of the machine toward the other scraper. The teeth 28 are held on the bar 27 in a similar manner to that of the teeth 25, by means of the plate 24' and the bolts 25'. The other end of the axle is formed with a crank portion 29, and on this portion there is mounted a ground engaging wheel 30.

The pockets are so constructed and arranged that they receive stones when at their lowermost points in the rotation of the large wheel and dump the stones at one side of the wheel when at their uppermost points, or approximately such positions. A wagon is arranged to be drawn along side of the large wheel to receive the stones which are discharged by the pockets. Thus stones from a field, road, or other place, can be effectively scraped up, lifted, and deposited in a receptacle for disposition at

some other point. The device is extremely simple and cheap in construction, and is effective in its operation.

Mounted on the frame 10, is the driver's seat 31. Mounted on the frame 17 is a toothed segment plate 17', and pivotally mounted on this plate and provided with a pawl 32 for engagement with the said teeth, is a lifting lever 33. This lever is formed with an arm 34 which is connected to the rear end of the bar 24 by means of the chain 35. Thus when the said lever is moved in one direction the rear end of the bar 24, together with the frame 10, will be elevated so that the teeth of the bars 24 and 27 will be held clear of the ground.

It will be noted that each of the pocket members is formed from a single piece of metal bent, as shown clearly in Figs. 1 and 20 4, whereby the stones which are scraped thereinto by the curved blade 36 will be held therein until the pockets reach such a height in the rotation of the wheel 19 that their contents will fall by gravity into the 25 chute 37, carried by the frame 17, and be discharged into the wagon. This blade 36 is carried by the rear end of the toothed bar 24. This blade guides and deflects the stones which are scraped rearwardly by the 30 teeth 25 so that they will be properly scooped into the pockets as said pockets successively dispose themselves at the lowermost point of the wheel 19.

What is claimed is:

35 1. A stone gatherer including a frame,

rearwardly converging scraping rakes on the frame, a movably connected frame carried by the first frame, a wheel carried by the movable frame and engaging the ground adjacent the converging ends of said rakes, 40 stone receiving pockets carried by the wheel, one of said rakes extending beyond the end of the other rake, and a scooping member on the said extended end of the scraping rake for guiding the stones into the pockets successively, said pockets being arranged to dump the stones adjacent the upper portion of the wheel.

2. A stone gatherer including a horizontal frame, rearwardly extending and converging bars rigidly secured to the lower side of the frame, said bars being provided with raking teeth, a ground engaging wheel disposed rearwardly of the frame, a frame pivotally connected to the first frame and supporting said wheel adjacent the converging ends of the said bars, pockets carried by and rotatable with the wheel, the rear end of one of said bars extending beyond the end of the other bar and adjacent the 55 said wheel, and a curved guiding and collecting blade carried by said end of the extending bar.

In testimony whereof we affix our signatures in the presence of two witnesses:

CHARLES E. CHASE.
OLIN E. HUTCHINGS.

Witnesses:

ALEX. VAN DYKEN,
CHAS. A. RUEUP.
